UNITED STATES PATENT OFFICE.

WILLIAM C. MEYER, OF BOSTON, MASSACHUSETTS.

DESIGN FOR A KNIFE.

SPECIFICATION forming part of Design No. 28,530, dated May 3, 1898.

Application filed March 14, 1898. Serial No. 673,872. Term of patent 14 years.

To all whom it may concern:

Be it known that I, WILLIAM C. MEYER, of Boston, county of Suffolk, and State of Massachusetts, have invented and produced a 5 new and original Design for a Knife, of which the following is a specification, reference being had to the accompanying drawing, forming a part thereof.

The drawing shows in perspective my newly-10 designed knife.

a represents a flat base having a circular hole a', located centrally, and b represents a flaring rim projecting at an angle from said base, as shown. The edge of said rim b is 15 beveled, as at b', and is also scalloped, as at

b². The inside of said rim b has a number of recesses or grooves b³, extending inward for a short distance and located at intervals apart.

I claim—

20 The design for a knife as herein shown and described.

In testimony whereof I have signed my name to this specification in the presence of two subscribing witnesses.

WILLIAM C. MEYER.

Witnesses:

B. J. NOYES,
J. L. HUTCHINSON.
